VISE MOUNTING

Everett M. Bush, South Nyack, N. Y.

Application September 17, 1938, Serial No. 230,406

4 Claims. (Cl. 81—41)

This invention relates to a vise mounting.

The main objects of this invention are to provide an improved vise mounting upon which vises of various sizes may be readily secured; to provide a vise mounting which is readily removable from a socket which is adapted to be secured to a truck body or other suitable foundation; and to provide a vise mounting of simple design which may be made by casting and which will require a minimum amount of machine work.

An illustrative embodiment of this invention is shown in the accompanying drawing, in which:

Figure 1 is a view in rear end elevation of a motor truck having a platform or stake body thereon upon which is mounted a socket and showing a vise mounting and vise secured thereto;

Fig. 2 is a view in perspective of the improved vise mounting;

Fig. 3 is a vertical medial sectional view showing the vise mounting in a socket; and

Fig. 4 is a sectional view taken along the line 4—4 of Fig. 3 looking in the direction indicated by the arrows.

In various kinds of construction and installation work, the crews of men are furnished with motor trucks which carry many and various kinds of tools and equipment for use on the job. One of the most frequently used tools in construction work is a vise, but to use a vise to the best advantage it should be located at the edge or corner of some foundation so that the workmen will have plenty of freedom for the article held by the vise, as well as for working upon such article. However, when vises are permanently affixed to the truck bodies at the rear edge or corners thereof, they are often in the way of doing other work and become a nuisance when not actually being used for holding some article. Therefore, it is highly desirable to have a vise which can be placed quickly at a point for advantageous use and at the same time be readily removable out of the way for other work. Inasmuch as vises usually have to be held very securely upon their foundation, such a removable vise has heretofore been impractical due to the fact that vises are ordinarily bolted to their foundation by three supporting bolts.

In the present construction, a vise of suitable size and character is securely bolted to the improved vise mounting and remains bolted thereto at all times. The vise mounting, however, is provided with a shank which slidably fits into a receiving socket, such being mounted upon the truck body with the top surface thereof flush

with the surface of the body so as to form no obstruction and which socket may be used for various other purposes, such as for receiving a pulley for a winch line or for receiving a cable clamp holder such as that described and shown in my copending application filed of even date herewith.

In the construction shown in the drawing, the mounting, generally designated 5, is shown in Fig. 1, with a vise 6 bolted thereto and the assembly mounted in a socket 7 which is secured to the body 8 of a motor truck at the rear end thereof.

The vise mounting 5 comprises a horizontal table top portion 8 of generally triangular shape having a depending flange or rim 9 integrally formed around the entire peripheral edge thereof. The table portion 8 is provided with three slots 10, 11, and 12, the slots 10 and 11 being in alignment with each other, one at each side of the longitudinal center of the device, and the slot 12 being at right angles with respect thereto. The slots 10, 11, and 12 extend through the top plate 8 and are adapted to receive the three attaching bolts customarily provided in the base of a vise, the slots being of sufficient length to receive the bolts of vises of various sized bases, i. e., various sizes of vises, as well as vises having two base attaching bolts.

The depending rim or flange 9 holds the under side of the top plate 8 in spaced relation to the mounting foundations, as shown most clearly in Fig. 3 of the drawing, so as to provide clearance or room for the heads of the bolts by which the vise 6 is secured to the top plate 8.

Means are provided for detachably mounting or positioning the vise mounting in a receiving socket and comprises an integrally formed hollow shank 13 of generally square or rectangular cross-section, the outside dimension of which is such as to be readily slidable within the socket 7. A horizontal partition wall 23 is integrally formed within the hollow shank in spaced relation to the top thereof so as to provide a shallow socket 24 for receiving the square boss which is provided on some vise bases. The wall 23 is provided with an aperture 25 therethrough for receiving a cap screw which threads into the vise base.

The shank 13, adjacent the lower end hereof, is provided with a removable cross-pin 14, upon which is slidably and pivotally mounted an eye 15 which is formed on one end of a shank or rod 16. The other end of the rod 16 is threaded to receive a nut 17 which adjustably positions and

secures a slidable sleeve 18 thereon. Sleeve 18 is provided with a laterally extending integrally formed finger 19, the outer end of which is turned upwardly to form a toe 20 which is adapted and positioned to engage the lower depending edge of the socket 7, as shown in Fig. 3 of the drawing for holding the improved vise mounting securely and rigidly within the socket 7. The socket 7 is rigidly secured to the truck body 8, flush with the top surface thereof, by means of attaching bolts 21 and 22.

In the use of this device, a vise of suitable size and desired character is bolted rigidly and securely upon the top table surface 8 of the improved vise mounting by one or more attaching bolts which pass through the slots 10, 11, and 12, or any of them, and the heads of which are housed within the base formed by the depending flange 9 which rests upon the surface of the foundation to which the device is attached. Should the vise be of the type which has a square boss on the base, the cross-pin 14 is slid axially to withdraw from the eye 15 and the pin and shank 16 removed, thus providing room for the insertion of a cap screw to be passed through the aperture 25 in wall 23 and screwed into the vise base. The cross-pin 14 and shank 16 are then replaced. The vise with its mounting may then be carried in a tool box or other suitable storage place in the motor vehicle and when it is desired to use the vise it is removed from its carrying or storage place and the shank 13 passed down into the socket 7.

The threaded shank 19 is then swung to one side, as shown in Figs. 3 and 4 of the drawing, and the upstanding toe 20 of the finger 19 engaged under the lower marginal edge of the socket, at which time the nut 17 is tightened up. It will, therefore, be seen that merely by the tightening of one nut the vise is rigidly mounted upon a foundation and is ready for use.

After use has been made of the vise, and its use is no longer desired, it may be readily removed and replaced in its storage or carrying compartment by merely loosening the nut 17 and allowing the shank 16 to swing to the side so as to clear the toe 20 from engagement with the socket 7.

In the structure illustrated, the shank and socket are square so that the mounting and vise may be placed in any one of four different positions, but it is to be understood that the shank and socket may be provided with any number of sides or may be round with splines or a key to prevent relative rotation.

Although but one specific embodiment of this invention has been herein shown and described, it will be understood that numerous details of the construction shown may be altered or omitted without departing from the spirit of this invention as defined by the following claims.

1. A vise mounting comprising a table portion adapted to receive the base of a vise, said table portion having slots therethrough for receiving the attaching bolts of said vise, a shank integrally formed on said table portion and adapted to be slidably received in a socket, said table portion having a depending flange around its peripheral edge for holding the under side thereof in spaced relation to a mounting foundation, thereby providing clearance for the heads of the vise attaching bolts.

2. A vise mounting comprising a table adapted to receive the base of a vise, said table having apertures therein for receiving the bolts for attaching said vise to said table, a hollow shank integrally formed on said table, and means carried within said hollow shank for detachably securing said shank within a shank receiving socket, said shank securing means comprising a pivotally mounted rod, the free end of said rod being threaded to receive an adjusting nut, a nut threaded on said rod, a sleeve slidably mounted on said rod and secured and adjusted by said nut, said sleeve having a laterally extending finger integrally formed thereon for engaging under the lower raw edge of a shank receiving socket.

3. A vise mounting comprising a table adapted to receive the base of a vise, said table having apertures therein for receiving the bolts for attaching said vise to said table, a hollow shank integrally formed on said table, and means carried within said hollow shank for detachably securing said shank within a shank receiving socket, said shank securing means comprising a transversely disposed pin secured to opposite side walls of said hollow shank, a rod pivotally and slidably mounted on said pin at its upper end, the lower end of said rod being threaded, a nut threaded on said lower threaded end, a sleeve slidably on said rod and secured thereon by said nut, a laterally extending finger on said sleeve, an upwardly turned toe on the outer end of said finger, said finger and toe being adapted to be engaged under the lower edge of a shank receiving socket.

4. A vise mounting comprising a table portion adapted to receive the base of a vise, said table portion having three slots therethrough, two of said slots being in alignment with each other and the third of said slots being at right angles with respect thereto, said slots being adapted to receive the bolts for attaching the vise base to said table top, said table top having a depending peripheral flange for spacing the under side of said table top from a mounting foundation surface, a substantially rectangular hollow shank integrally formed on said top member and extending normal with respect to the plane thereof, said shank being adapted to be slidably received within a shank receiving socket, a pin transversely disposed within said hollow shank and having its opposite ends secured in opposite walls thereof, a rod swingably and slidably mounted on said pin, a socket engaging clamping sleeve slidably mounted on said rod, and a nut threaded on said rod for securing said sleeve.
